[57] CLAIM

The ornamental design for a lady's shoe heel protector, as shown and described

DESCRIPTION

FIG. 1 is a perspective view of a lady's shoe heel protector showing my new design;

FIG. 2 is a left side elevational view thereof;

FIG. 3 is a rear elevational view thereof;

FIG. 4 is a top plan view thereof;

FIG. 5 is a bottom plan view thereof.

FIG. 6 is a rear elevational view thereof.
